(57) **CLAIM**

The ornamental design for an automotive tent, as shown and described.

DESCRIPTION

FIG. 1 is a top front perspective view of an automotive tent showing my new design;

FIG. 2 is a top rear perspective view thereof;

FIG. 3 is a bottom front perspective view of the automotive tent shown with alternative broken line subject matter;

FIG. 4 is a bottom rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken line showing is for the purpose of illustrating portions of the automotive tent that form no part of the claimed design.
